(57) CLAIM

The ornamental design for a locking lug pick for firearm cleaning, as shown and described.

DESCRIPTION

FIG. 1 is a perspective view of a locking lug pick for firearm cleaning depicting the novel design;

FIG. 2 is a right side elevational view thereof, the left side view being a mirror image thereof;

FIG. 3 is a front elevational view thereof;

FIG. 4 is a rear elevational view thereof;

FIG. 5 is a top plan view thereof; and,

FIG. 6 is a bottom plan view thereof.

The broken lines shown in the drawings represent unclaimed portions of the design and form no part thereof.
